UNITED STATES PATENT OFFICE.

STANLEY W. HAYES, OF RICHMOND, INDIANA, ASSIGNEE TO HAYES TRACK APPLI-
ANCE COMPANY, OF RICHMOND, INDIANA, A CORPORATION OF INDIANA.

DERAIL.

Application filed July 21, 1922. Serial No. 576,425.

To all whom it may concern:

Be it known that I, STANLEY W. HAYES, United States citizen, residing in Richmond, county of Wayne, and State of Indiana, have invented the following described Improvements in Derails.

In derails as made in accordance with modern practice, the body or guiding portion of the derailing member is usually of considerable extent especially in derails of the sliding type and the entire derailing member is a single and necessarily intricate casting. The production of such castings presents difficulties since irregularities or inequalities in cooling set up internal strains in the casting at the places cooled at a different rate from the adjacent metal, these places of initial and permanent strain being danger points at which the casting may give way under the added strains incident to use.

This difficulty would be increased almost or quite to the point of impossibility were the attempt made to use manganese steel which is difficult to cast and heat-treat even in simple form.

This invention overcomes this difficulty by making the derail block, whether cast or not, separate from the body of the derailing member, and mounting it on the body of the derailing member in any suitable way, preferably by a detachable joint at the junction of the transversely extending body and the longitudinally extending derail block.

The invention further provides for making the derail block and the derailing body of metal of different character, which is sometimes desirable, as where the derail block is made of pressed steel or manganese steel and the body of other steel alloy, and for interchangeability of derail blocks to accommodate the derail to different conditions by mounting any one of the derail blocks on the single body portion of the derailing member.

Referring to the single sheet of drawings, Figure 1 is a vertical longitudinal section showing the derail in open position; Figure 2 is a detail rear elevation partly in section of the derail block and the body of the derailing member shown separated. Figure 3 is a detail rear elevation showing the derail block and the body of the derail-

ing member fastened together detachably; 55 and Figure 4 is a plan view partly in section showing the socket part of the joint.

My invention, while not limited to derails of the sliding type, is especially applicable thereto, and in the drawings I have illustrated a derail of that type, the details of which have not been completely shown since my invention does not reside therein. The derail is however, generally speaking, of the sort disclosed in my prior patent No. 65 1,306,961, of June 17, 1919. In the illustrated derail the side wall 1 of the base is connected by the forward cross wall 2, the roof member 3 and the rear wall 4, the other side wall not being shown. This base furnishes 70 forward and rear bearings indicated respectively at 5 and 6, the upper lug 7 being also regarded as a part of the rear bearing. The derailing member comprises a derail block proper 8, and a supporting body 9 therefor 75 which is contained in and guided by the base. The forward bearings are constituted in the form illustrated of studs 10 extending outward from opposite sides at the forward end of the body, and slidable on the 80 forward bearing grooves 5. The rear bearing consists of a central upstanding hook shaped rib 11 mounted slidably in and between the rear bearing lugs 6-7. The derail block 8 is separately made and firmly 85 attached to the body of the derailing member preferably by a joint in the nature of mortise and tenon which may take various forms one of which is that illustrated. It is evident however, that quite different 90 mountings may be employed, and it will be observed that the derailing member is T-shaped, its body 9 constituting the stem of the T and its derail block 8 the cross bar, and that the joint is located at the intersection of the stem and cross bar portions. In the drawings, the body 9 of the derailing member has a substantially upright forward shoulder portion 12 forming a socket parts of whose inner walls 13 are designed for contact with the corresponding faces 14 of a tenon part 15 projecting from the bottom of the derail block 8, thus constituting an upwardly opening vertically socketed joint. This mortise and tenon or socket joint irrespective of bolts or other securing means furnishes ample bearing surface to take the thrust in all directions. I prefer to provide

95

100

105

the derail block at its front side with a depending flange 16, the inner face of which is adapted to contact with the outer face of the corresponding part of the body of the 5 derail and which assists in resisting strain. The underside 17 of the derail block is formed to make a proper bearing on the upper surface of the upright portion 12 of the body of the derailing member. This bearing 10 is preferably located at a level which is substantially that of the rail tread, when the derail is open, or to speak more exactly, which is adjacent to the top of the corner of the rail head.

15 A pair of bolts 18, passed through registering holes 20 and 21 in the body and block respectively and with their heads seated in square countersinks 22 serves to secure the parts in assembled relation and 20 to resist spreading of the socket under strain, but permit the removal of the derail block when desired. It will be understood that the derail block may be of any suitable contour, for derailing in either or both directions, the block shown being provided 25 with a hand hole 23 for operating the derail by hand when desired.

It may be noted in conclusion that the upwardly opening mortise and tenon joint between the derail block and the body of the derailing member is particularly efficacious 30 in respect to maintaining its integrity under the unusually severe strains to which derailing members are subjected and against 35 which they must be proof, the practicability of a derailing member composed of separately made parts being conditioned on the strength of the joint between such parts, and the character and location of the joint being 40 thus vitally important. By locating the upwardly opening mortise and tenon joint at the widest part of the body, so that the joint itself is wider than the body except at that part, the quality of dependability essential 45 to a derailing member is enhanced and this characteristic further assured by the spread-preventing action of the bolts as respects the mortise or socket.

Claims:

- 50 1. In a derail, a derailing member having a body and a detachable derail block of metal differing in character from that of the body.
2. In a derail, a derailing member having 55 a derail block portion and a body portion both of metal made as separate parts and secured together.
3. In a derail, a derailing member having a body and a derail block both of metal 60 made as separate parts and secured together at the widest part of the body.
4. In a derail, a derailing member having a body or guiding portion extending transversely of the rail and a derail block portion 65 extending longitudinally parallel with

the rail, made separate from said body and secured thereto.

5. A derail having a base, a derailing member mounted thereon having longitudinal and transverse portions, and a rigid 70 separable joint connecting said portions.

6. In a derail, a derailing member having a body or guiding portion extending transversely of the rail and a derail block portion extending longitudinally parallel with 75 the rail, and a detachable joint at the junction of said transverse longitudinal portions.

7. In a derail, a T-shaped derailing member whose stem and cross-bar made as separate parts are rigidly secured together at 80 their junction.

8. A derail having a base, a T-shaped derailing member mounted thereon with the stem of the T extending transversely of the rail, and a rigid separable joint at the junction of the stem and cross bar of the T. 85

9. In a derail, a derailing member having a body and a detachable derail block supported on the body, said body and block having contacting joint surfaces preventing 90 relative movement toward, from or endwise of the rail.

10. In a derail, a derailing member having a derail block portion and a body or guiding portion made as separate parts and connected by mortise and tenon joint. 95

11. In a derail, a derailing member having a derail block portion and a body portion connected by an upwardly opening vertically socketed joint. 100

12. In a derail, a derailing member having a body and a detachable derail block resting secured to and bearing on said body near its forward end in substantially the plane of the rail tread when the derail is open. 105

13. A derail of the sliding type comprising a base, and a derailing member mounted on bearings on said base to slide to and from the rail and having a body adapted to receive any one of a variety of derail blocks 110 and a derail block detachably secured to said body.

14. In a derail, a derailing member having a body extending transversely of the rail and provided at its front end with a socket, 115 a derail block having a projection fitting said socket, and means for detachably securing the derail block to the body with the projection in the socket.

15. In a derail, a derailing member having a body and a derail block made as separate parts and detachably secured together with contacting joint surfaces located in the open position of the derail adjacent the rail and at substantially the level of the rail tread. 120

16. In a derail, a derailing member having a body provided with a forward upright portion and a detachable derailing block supported on said upright portion, said derailing block and upright portion having 130

contacting joint surfaces located in the open position of the derail in substantially the plane of the rail tread.

17. In a derail, a derailing member having a body extending transversely of the rail and provided adjacent the rail with an upwardly opening socket, a derail block

having a projection fitting said socket, and spread-preventing means for the socket securing the projection therein. 10

In testimony whereof, I have signed this specification.

STANLEY W. HAYES.
